Primary Examiner — Patricia A Palasik(74) *Attorney, Agent, or Firm* — Burns & Levinson LLP(57) **CLAIM**

The ornamental design for a mobile robot, as shown and described.

DESCRIPTION

FIG. 1 is a perspective view of a mobile robot from above the mobile robot;

FIG. 2 is a perspective view of the mobile robot from below the mobile robot;

FIG. 3 is a front view of the mobile robot;

FIG. 4 is a back view of the mobile robot;

FIG. 5 is a left side view of the mobile robot;

FIG. 6 is a right side view of the mobile robot;

FIG. 7 is a plan view of the mobile robot showing a bottom of the mobile robot;

FIG. 8 is a plan view of the mobile robot showing a top of the mobile robot; and,

FIG. 9 is a perspective view of a corner of the mobile robot.

1 Claim, 9 Drawing Sheets(56)
